Assistant Examiner — Nathan M Johnston

(74) Attorney, Agent, or Firm — Woodard, Emhardt,
Moriarty, McNett & Henry, LLP; Charles Meyer(57) **CLAIM**

The ornamental design for a medical apparatus, as shown and described.

DESCRIPTION

FIG. 1 is a perspective view of the medical apparatus showing my new design.

FIG. 2 is a lower perspective view thereof.

FIG. 3 is a front elevation view thereof.

FIG. 4 is a rear elevation view thereof.

FIG. 5 is a first side elevation view thereof.

FIG. 6 is a second side elevation view thereof.

FIG. 7 is a top plan view thereof; and,

FIG. 8 is a bottom plan view thereof.

1 Claim, 5 Drawing Sheets(56)
